UNITED STATES PATENT OFFICE.

CHARLES SCHEUER, OF NEW YORK, N. Y.

DESIGN FOR A POCKET-BOOK, CASE, OR WALLET.

SPECIFICATION forming part of Design No. 22,362, dated April 25, 1893.

Application filed September 23, 1892. Serial No. 446,733. Term of patent 3½ years.

To all whom it may concern:

Be it known that I, CHARLES SCHEUER, a citizen of the United States, residing in New York city, in the county and State of New York, have invented and produced a new and original Design for a Pocket-Book, Case, or Wallet, of which the following is a specification.

Reference is to be had to the accompanying drawings forming a part of this specification, in which similar letters of reference indicate corresponding parts in both the figures.

Figure 1 is a front perspective view of a card case showing my design; and Fig. 2 is a rear perspective view of the same.

The leading feature of my design consists

in an envelope-like figure A, covering the outer surface of the article in such a manner that the front or obverse B, of the envelope appears on one-half of the article's surface, and the reverse C of envelope is on the other half surface of the article, as plainly illustrated in the drawings. The obverse B is ornamented with a figure D, simulating a canceled stamp.

I claim—

The design for a pocket book, case or wallet as herein shown and described.

CHARLES SCHEUER.
